UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A LAMP-FOUNT HOLDER.

SPECIFICATION forming part of Design No. 24,612, dated August 20, 1895.

Application filed July 22, 1895. Serial No. 556,830. Term of patent 3½ years.

To all whom it may concern:

Be it known that I, FRANZ YOKEL, of Meriden, in the county of New Haven and State of Connecticut, have invented a new Design 5 for a Lamp-Fount Holder, (Case B;) and I do hereby declare the following, when taken in connection with the accompanying drawing and the letters of reference marked thereon, to be a full, clear, and exact description of the same, and which said drawing constitutes part 10 of this specification, and represents a perspective view of a lamp-fount holder embodying my design.

This invention relates to a design for a lamp- 15 fount holder, and it consists in the configuration and ornamentation as shown in the accompanying drawing.

The holder is of bowl-like character. The 20 central portion B of the bowl is plain, and around the upper edge of the bowl and de-

pending over the plain portion B is a circumferential band C, ornamented by lattice-work, scrolls, and floriated figures. Surrounding the base of the bowl and overlapping the said plain portion B is a circumferential band D, 25 ornamented by scroll figures and medallions. This band D is contracted, forming the ornamental base A, all as shown in the accompanying illustration.

I claim—

The design for a lamp-fount-holder as herein described and shown in the accompanying illustration.

In testimony whereof I have signed this specification in the presence of two subscr- 35 ing witnesses.

FRANZ YOKEL.
